Primary Examiner—Ted Shooman
Assistant Examiner—C. Tuttle**[57] CLAIM**

The ornamental design for a combined hook-and-loop material door-holding door stop and receiver therefor, as shown and described.

DESCRIPTION

FIG. 1 is an exploded perspective view of the hook-and-loop material door-holding door stop and receiver therefor; FIG. 2 is an exploded top view of the design, the side opposite being a mirror image thereof; FIG. 3 is a side view thereof, the side opposite being a mirror image thereof; FIG. 4 is a front view of the receiver component of the design, shown separately for clarity; FIG. 5 is a rear view of the receiver component; FIG. 6 is a front view of the door stop component the design, shown separately for clarity; FIG. 7 is a rear view of the door stop component; FIG. 8 is an assembled side view of the door stop and the receiver therefor; and, FIG. 9 is an assembled top view of the door stop and the receiver therefor. The broken lines are for illustrative purposes only, and form no part of the claim.
